UNITED STATES PATENT OFFICE.

MOSES J. MOSS, OF NEW YORK, N. Y.

CLOTH STEAMING AND FOLDING APPARATUS.

1,247,311.

Specification of Letters Patent. Patented Nov. 20, 1917.

Application filed March 20, 1917. Serial No. 156,101.

To all whom it may concern:

Be it known that I, MOSES J. Moss, a citizen of the United States, and a resident of the borough of Manhattan, city, county, and State of New York, have invented certain new and useful Improvements in Cloth Steaming and Folding Apparatus, of which the following is a specification.

My improvements relate to apparatus for 10 "sponging" or steaming and refolding cloth, and are designed to effect economy in the time and labor involved, as well as a saving in floor space for a given capacity of work.

The invention consists in the specific construction and arrangements of parts herein described and claimed, distinctive features being the positioning of duplex steaming cylinders the one above the other so that they may be alternately but continuously 20 used for steaming the cloth in such manner that the latter may be transferred from said steam cylinders directly to the refolding mechanism, all as hereinafter more fully set forth.

25 In the accompanying drawings,

Figure 1, is a plan of apparatus embodying the essential features of my invention;

Fig. 2, is a side elevation thereof;

Fig. 3, is a vertical cross section taken 30 upon plane of line 3—3, Fig. 1;

Fig. 4, a vertical cross section upon plane of line 4—4, Fig. 1.

As is well known in the art twin steaming cylinders have heretofore been positioned 35 side by side in horizontal relationship to each other, but have been operated independently. In other words their being mounted on a common frame, etc., has been merely a matter of convenience and economy 40 of floor space, etc., and each has been operated separately, the steamed cloth from each being wound by manual means onto a separate transfer spindle which was lifted and carried bodily to detached refolding mechanism constituting a separate unit in the 45 system.

The main objects of my invention are, to effect the continuous but alternate operation of a plurality of correlated steaming cylinders in such manner that the treated cloth can be unwound therefrom directly by and onto refolding and rewinding mechanism forming a component part of the apparatus as a whole, thus eliminating the transfer 50 spools and the time and labor involved in their use, keeping the refolding and winding

mechanism constantly employed, and attaining the maximum of work from the steaming cylinders, on one of which cloth can be wound and steamed while the finished cloth 60 is unwound from the other by the refolding and rewinding mechanism.

To this end I arrange one steaming cylinder S' , on a higher level than its companion cylinder S^2 , preferably (but not necessarily) 65 in vertical alinement or substantially so, as shown in the drawings, so that both said steaming cylinders may take direct from the feed tension guide-rolls f , f , and both may feed direct to the tension roller r , which delivers the cloth to the table r' , of the refolding and rewinding mechanism R , which latter is incorporated as a component part of the apparatus considered as a whole, and as treating the cloth continuously from the 70 time it is fed to the steam cylinders until it is again wound in folded condition on a bolt board or equivalent receiving spool e , ready for the market or manufacturing purposes. 80

Thus the frame work b , b , for the steaming mechanism S , and for the refolding and rewinding mechanism R , is supported upon a common base B , and the apparatus is further incorporated in a unitary structure by 85 the tension feed roller r , and receiving table r' , interposed directly between said steaming and refolding mechanisms.

Each peripherally perforated steaming cylinder S' , S^2 , is rotatably mounted on a 90 fixed hollow axle s' , s^2 , through which steam is fed to the interior of said cylinder. Any of the steaming or refinishing cylinders known in the art may be used in this connection, according to the treatment to be administered to the cloth,—the steam in any case being injected through peripheral openings into the cloth wound around the cylinder in a manner well known in the art. 95

Thus in the drawings, the axle pipes s' , 100 s^2 , are mounted rigidly upon and between stationary parts b' , b' , of the frame work b , b , supported as aforesaid on the common base B , and are supplied with steam by pipe connection s^3 , s^4 , provided with valves 105 s^5 , s^6 ,—the portion of each axial pipe within its cylinder being perforated to admit steam to the latter. Each cylinder S' , S^2 , carries rigidly attached to it a pulley s^8 , by which it may be independently rotated,—said pulleys s^8 , s^8 , being each connected by a separate belt a , a , with a loose pulley d , on the 110

driving shaft D, mounted in suitable bearings b^2 , b^2 , (see Fig. 3) on the frame b , b , of the base B, below the cloth steaming cylinders S', S².

- 5 C, is a double-faced clutch splined to the shaft D, to rotate therewith,—each of its faces being serrated or otherwise formed for positive engagement with the correspondingly formed and adjacently opposed hub 10 face of one of the pulleys d, d, so that the said pulleys d, d, may be alternately rotated by shifting the clutch C, which may be accomplished by the hand lever e, or equivalent mechanical expedient. Hence either of 15 the cloth steaming cylinders S', or S², may be separately rotated, but one only at a time, by positive means, for the purpose of winding the unfolded web of textile fabric w, thereon,—said web w, (see Fig. 2) of cloth 20 being fed to the receiving table s', on its way to the feed tension rollers f, f, from a truck T, traveling on rails t, t, which insure the proper alinement of the web w, with relation to said feed rollers f, f, and cloth 25 steaming cylinders S', S².

Power is borrowed from the driving shaft D, through the medium of the clutch C, and appropriate pulleys and belts to rotate each cloth steaming cylinder while the web of 30 cloth w, is being wound thereon,—the other cloth steaming cylinder meanwhile being loosely rotatable on its axis pipe. Thus, since a minute is ordinarily sufficient to effect the saturation of the cloth, the latter 35 may be steamed on, and withdrawn from, one cloth steaming cylinder while a fresh bolt of cloth is being positively wound upon the other cloth steaming cylinder, thereby practically rendering the operation of the 40 apparatus continuous.

- The steamed cloth on the cylinder which is disengaged from the power mechanism is passed under the tension feed roller r, over the guide table r', and to the inclined fold 45 bars r², r², through which it is threaded in the usual manner to and around the under side of the idler roller r³, by which it is delivered to the receiving spool e, (usually a flat cloth board) which is secured between 50 suitable clutch mechanism which is rotatable by means well known in the art,—the power applied to effect the receiving spool e, being utilized to draw off the steamed cloth from either steam cylinder, and to refold 55 and rewind such steamed cloth ready for commercial disposal or use.

The positive rotation of the cloth board or receiving spool e, which is held between the usual clamps r⁴, is effected by suitable 60 rotative mechanism, as by sprocket wheels r⁵, and chains r⁶, r⁶, driven from the power shaft r⁷, or by any other mechanical expedient, in a manner well known in the art.

This utilization of the power required for

refolding and rewinding the cloth is the 65 essential, distinguishing and important feature of my invention, since I thereby economize power, time and labor,—the tedious and laborious task of winding the cloth by hand from a cloth steaming cylinder to a portable spindle, and lifting and transferring this portable spindle bodily from the steaming apparatus as an independent machine in the system to the refolding and rewinding machine as another and distinct machine in 70 the system of cloth finishing, being entirely eliminated. When it is considered that a loaded transfer spindle such as heretofore used, requires the strength of two men to 75 lift it from the steaming mechanism and position it in the refolding and rewinding mechanism, it is obvious that my improvement is an important advance in the art of cloth-finishing. It not only saves the time and labor involved in manually transporting the old transfer spindle from one apparatus to another, but it also saves the time heretofore required to wind the cloth thereon, and then to unwind it therefrom. In 80 fact it dispenses entirely with one manipulation of the cloth, and thereby shortens and cheapens the process of cloth finishing considered in its entirety, and renders the process 85 essentially continuous in a single apparatus. I am thus enabled to effect a saving 90 of two thirds of the time heretofore required to steam and rewind the cloth because from the time of the start of the wind of the cloth onto the steaming cylinder until the rewind 95 on the receiving spool there is no rehandling 100 thereof, nor delay in passing it continuously through my unitary apparatus.

Furthermore, by my combination and arrangement of operative parts on one frame and base in compact form and relationship 105 much economy is effected in floor space,—an item of great importance under ordinary conditions of use.

What I claim as my invention and desire to secure by Letters Patent is,

1. In cloth steaming and folding apparatus of the character designated, in combination, a plurality of rotatable cloth steaming cylinders arranged one above the other, and cloth refolding mechanism positioned and adapted to unwind the steamed cloth from either of said cloth steaming cylinders and to refold the steamed cloth so unwound and rewind it in such folded condition onto a receiving spool and a receiving table interposed directly between the steaming and refolding mechanisms whereby the treatment is continuous.

2. In cloth steaming and folding apparatus of the character designated, in combination, a plurality of rotatable cloth steaming cylinders arranged one above the other, feed tension rollers positioned to feed unfolded

cloth to either of said cloth steaming cylinders, and cloth refolding mechanism positioned and adapted to unwind the steamed cloth from either of said cloth steaming cylinders and to refold the steamed cloth as unwound and rewind it in such folded condition onto a receiving spool and a receiving table interposed directly between the steaming and refolding mechanisms whereby the treatment is continuous.

3. In cloth steaming and folding apparatus of the character designated, in combination, two rotatable cloth steaming cylinders arranged one above the other, a pair of feed rollers positioned to feed unfolded cloth to either of said cloth steaming cylinders, and cloth refolding mechanism positioned and adapted to unwind the steamed cloth from either of said cloth steaming cylinders and to refold the cloth so unwound and rewind it onto a receiving spool and a receiving table interposed directly between the steaming and refolding mechanisms whereby the treatment is continuous.

4. In cloth steaming and folding apparatus, steaming mechanism embodying a plurality of steaming cylinders, cloth refolding mechanism, an interposed receiving table, and a tension roller interposed between the steaming mechanism and said receiving table and adapted to feed the steamed cloth from either of the cylinders of the steaming

mechanism to the cloth refolding mechanism.

5. In cloth steaming and folding apparatus, steaming mechanism embodying a plurality of steaming cylinders, cloth refolding mechanism, an interposed receiving table, a tension roller interposed between the steaming mechanism and said receiving table and adapted to feed the steamed cloth from either of the cylinders of the steaming mechanism to the cloth refolding mechanism, and inclined fold bars leading from said receiving table to deliver the steamed cloth to the receiving spool.

6. In cloth steaming and folding apparatus, steaming mechanism embodying a plurality of steaming cylinders, cloth refolding mechanism, an interposed receiving table, a tension roller interposed between the steaming mechanism and said receiving table and adapted to feed the steamed cloth from either of the cylinders of the steaming mechanism to the cloth refolding mechanism, inclined fold bars leading from said receiving table to deliver the steamed cloth to the receiving spool, and an idler roller interposed between said inclined fold bars and the receiving table.
